WILMUTH E. BLACKBURN, OF SUMMIT, NEW JERSEY.

INDICATING MECHANISM FOR GAME APPARATUS.

1,377,869.

Specification of Letters Patent. Patented May 10, 1921.

Application filed February 25, 1919. Serial No. 279,103.

To all whom it may concern:

Be it known that I, WILMUTH E. BLACKBURN, a citizen of the United States, residing at Summit, in the county of Union, State of New Jersey, have invented certain new and useful Improvements in Indicating Mechanism for Game Apparatus, of which the following is a specification.

This invention relates to improvements in indicating mechanisms, pertaining more particularly to mechanisms of the accumulative type adapted for use in connection with game apparatus.

This invention is of the general type disclosed in my companion applications for game apparatus, filed August 21st, 1917, Serial No. 187,327, and Serial No. 244,257, filed July 10, 1918, in that I employ a target in rear of a ball runway, the latter having its rear portion curved upwardly to cause a ball or missile to be trajectory upwardly into contact with a baffle when caused to travel in the direction of length of the runway, the target carrying a plurality of pockets into either of which the ball may fall after its contact with the baffle, the ball then being operative in tripping suitable mechanism forming part of an accumulative indicating structure normally hidden from view but adapted to expose an indication representing the accumulations.

The present invention pertains more particularly to the indicating mechanism portions of such apparatus, differing from the prior form in that the indications employed are carried by a suitable indication carrying member, which may be in the form of a web, movable relative to the exposure opening, the tripping mechanism being operative to cause a succession of web movements of varying length according to the particular value of the pocket into which the ball or missile may fall, the shifting of the web exposing a new indication representing the value of the pocket added to the amount of the previous indication.

The objects of the invention are to provide a construction of this type which is simple and efficient in operation, durable in construction, and which can be manufactured at a relatively low cost.

To these and other ends, therefore, the nature of which will be readily understood as the invention is hereinafter fully disclosed, said invention consists in the improved construction and combination of parts, herein-

after fully described, illustrated in the accompanying drawings, and more particularly pointed out in the appended claims.

In the accompanying drawings, in which similar reference characters indicate similar parts in each of the views—

Figure 1 is a perspective view of a game apparatus, of the general type referred to and in which the present invention is embodied.

Fig. 2 is a side elevation of the indicating mechanism, parts being omitted and others broken away.

Fig. 3 is a front elevation of the same, with parts left off for the sake of clearness.

Fig. 4 is a fragmentary detail of a portion of a support, and

Fig. 5 is a detail inverted perspective view of the controlling elements or tumblers employed in the control of the length of web shifting movements.

In Fig. 1 I have shown the general arrangement of the game apparatus, the target being indicated at *a*, the ball runway at *b* with the inclined portion *b'*, the balls or missiles at *c*, the baffle at *d*, and the goals or pockets at *e*, *e'* and *e''*, these having different values according to the difficulty of pocketing the ball therein. For instance, goal *e* may have a value of fifty points, goal *e'* thirty points, and goal *e''* twenty points, goal *e* being the more difficult to pocket owing to its size and location.

In playing the game a contestant is given a definite number of balls or missiles—ten, for instance—which are rolled successively over the runway, contacting with the baffle and then passing into one of the pockets or goals, each of the latter having a passageway *f* leading from the pocket through which the delivered ball travels and down an offset chute not shown to the tripping mechanism individual to the pocket, thus setting in motion the indicating mechanism to produce the proper indication, the next ball serving to add the value of its goal to the previous indication.

One embodiment of the present invention is more particularly shown in Figs. 2 to 5 wherein 10 indicates a supporting frame, arranged in rear of the target, and in which is mounted a supply drum 11 and a collection roll 12, these having secured thereto the opposite ends of a web 13, the particular embodiment shown being of the web type to permit of the use of a large number of indi-

cations, it being preferred to use the single drum 11—with the indications arranged on its periphery—where the number of indications are materially decreased.

5 The shaft of drum 11 carries a pulley or sheave 11^a to which is secured one end of a cable 14 which leads downwardly over idlers and is then carried forward and connected to a resetting mechanism shown as in the 10 form of a lever 15, the connection being indicated as in the form of a rod 14^a, although the cable may lead direct to the lever. The arrangement is such that as the drum is rotated in the direction of accumulative 15 advance of the web, the cable is wound upon its sheave—a suitable amount of slack being provided for the purpose—so that when the lever is shifted to reset the indicator, the unwinding of the cable will rotate drum 11 in 20 the opposite direction.

The shaft of roll 12 also carries a pulley or sheave 16 on which is mounted a cable 17 carrying a weight 18, the direction of wind of this cable being such that as the web is 25 withdrawn from the roll during the resetting operation, the cable will be wound on its sheave, the weight then acting as the power to shift the positions of the drum and roll as the tripping mechanism permits the 30 web forming the connection between drum and roll for the purpose.

Where drum 11 only is used, the two 35 sheaves would be carried by the drum shaft, this being a well-known form of mechanism for rotating a drum in opposite directions.

The web carries a succession of indications—shown as numbers—indicating values, these being arranged in uniform progression, with the indication of least value—40 generally zero—forming the first indication from the end secured to roll 12, the particular arrangement shown providing progression by tens. For a purpose presently described, the zero or starting indication is so 45 arranged on the web that when it is opposite the exposure opening of the target—indicated at *h*—a portion of the web will be wound upon the roll; in other words, the arrangement is such that the particular portion 50 of the web carrying the starting indication can be carried beyond the exposure opening during the resetting operation, although the completion of this operation finds this indication in proper position relative to the exposure opening, this being provided by a return of the web under the action 55 of weight 18 after the indication has been moved past the opening.

The major portion of the web is normally 60 wound on drum 11, the latter, at the close of the resetting operation, acting to restrain the weight from advancing the web from its position of exposing the starting indication, until the tripping and web-movement 65 controlling mechanisms release the drum

and permit the weight to draw the web onto roll 12.

Drum 11 carries an annular series of pins or rods 20 extending parallel to the drum axis, these rods being shiftable longitudinally to control the amount of projection on the front of the drum and acting on the order of an escapement structure to determine the length of angular movement of the drum under the action of the weight. 75

The shifting movements of the rods or pins 20 are provided in the following manner:

Located in front of the drum, and mounted on a suitable rod or pivot 21, are a plurality of tumblers 22, 23 and 24—three being shown in correspondence with the number of goals. The tumblers are arranged side by side and may, as shown, be of different sizes, each being of suitable configuration, shown as triangular, and have their forwardly projecting portions resting on arms 25 projecting upwardly from the rear ends of levers 26, 27 and 28 mounted on brackets 29 carried by the frame. The levers correspond with the number of goals—one for each goal—and as the ball or missile travels from the goal to a return runway, it passes into contact with the corresponding lever, rocking the latter to raise 90 its arm and thereby rock the particular tumbler which is being supported by the arm.

The tumblers are positioned relative to the pins in such manner that this rocking movement of a tumbler serves to shift the pin or 100 pins which may be in rear of it in a rearward direction, thereby taking them out of the plane of an upright 10^a which forms a part of the frame and which forms an element of the escapement structure, it being 105 understood that a projected pin will contact with the upright and prevent advance of the drum, and when the pins are shifted, this restraint is eliminated by the movement of the pins. 110

The tumblers—shown inverted in Fig. 5—are so arranged that tumbler 22—that for goal *e*²—is located adjacent the upright, and since the goal value represents two of the tens, it is of a size and so positioned as 115 to be effective on the two pins that may be projected in immediate advance of the upright—the first pin being that which is providing the drum restraint. Hence, when the ball from goal *e*² passes into contact 120 with lever 26 and shifts the position of tumbler 22 rearwardly, drum 11 is free to advance angularly a distance sufficient to bring the next pin—still projected—into contact with the upright, thus again restraining the 125 advancing movement, the distance traveled being such as to advance the web a distance of two indications, so that the exposed indications will indicate a value of two tens greater than the previous exposure. 130

Tumbler 23—operated by a ball from goal e' —is adjacent tumbler 22, and when actuated shifts the third pin. This shifting would be of no avail, however, unless the two pins in rear of tumbler 22 were concurrently shifted, and hence there is a connection between these tumblers 22 and 23, this connection being in the form of a recess 23^a carried by tumbler 23 and a pin 22^b carried by tumbler 22, the recess permitting tumbler 22 to operate alone, while the pin and recess connection causes a movement of both tumblers when tumbler 23 is operated, so that movement of tumbler 23 serves to shift three pins, and permits the drum to advance the angular distance corresponding to a shifting of the web for a distance of three tens indications. A similar pin 23^b and recess 24^a on tumblers 23 and 24 provide this joint movement when tumbler 24 is actuated, the movement of this tumbler thus concurrently moving all of the tumblers and shifting five pins—representing the value of five tens in the web indications.

From this it will be understood that each pin represents a value of one ten step in the indication progression—one ten in the particular embodiment shown, and it therefore becomes necessary only that the tumblers be so formed as to shift the number of pins which represents the total number of steps represented by a goal value. At the end of each advance movement of the drum a new set of pins is located in rear of the tumblers, ready for the succeeding operation under which the web is advanced from the last position the number of tens corresponding to the number of pins shifted. As a result, the number of pins employed in the drum becomes more or less immaterial, since the drum may be rotated a plurality of times in unwinding a lengthy web with many indications, each advance positioning a new set of pins for operation.

As will be understood, the successful operation of this escapement structure is dependent upon the presence of projected pins when opposite the tumblers, while the tripping mechanism shifts these pins into the opposite position. To provide the return shifting action so as to reset the pins after the tumblers have been actuated, I employ a roller 30 or other form of structure—operating in the nature of a cam—on the rear side of drum 11 and in the path of the pins which have been shifted rearwardly, the cam being shown as supported by the frame and located at a point where at least a sufficient number of pins will be projected during drum travel in the direction of the arrow in Fig. 3, to insure projected pins in rear of the several tumblers plus one pin. In the drawings I have shown the position of the cam so as to provide for two addi-

tional pins, this, of course, being illustrative only.

As a result, it will be understood that while the tumblers operate to shift pins rearwardly in accordance with values, thus providing drum advance angularly, such advance automatically restores the pins to projected position as each passes the cam roller 30, so that a constant supply of projected pins is present to permit the web advance to any point within the limits permitted by its length on the drum.

In playing the game, the apparatus is reset before the beginning of the operation by the succeeding player, this being provided by actuation of lever 15, the movement of which serves to rotate drum 11 in the opposite direction.

As will be readily understood this reverse movement of the drum brings certain difficulties to the fore. For instance, the actual drum-holding pin—that in contact with the upright—must be projected to serve its purpose in the succeeding operation, and yet it must be shifted in order to pass the upright during the advance. Hence, these pins shifted rearwardly during the advance and which have not reached roller 30 are in the retracted position and while capable of passing the upright during the return are not in position to provide drum-holding action; on the other hand, these pins which have passed the roller are projected and therefore must be retracted before they can again pass the upright during the return movement.

To meet these conditions, I have provided a cam-face 10^b in upright 10^a—see Fig. 4—this cam face being so positioned to shift rearwardly any projecting pins which may be present in the succession of pins passing the upright during the return movement, thus permitting free return movement of the drum regardless of whether it has made a plurality of revolutions during the advance or less than a single revolution. As will be understood, the retracted pins during the return movement of the drum will be again projected by roller 30 whenever they reach this roller during this movement, but since they are again shifted rearwardly by cam-face 10^b, this projecting action has no effect on the operation.

It is by this action of roller 30 that the resetting operation is completed, the presence of the extra web portion heretofore referred to, permitting the web to be carried a distance sufficient to cause the particular pin which may represent the zero or starting indication, to reach roller 30 during this return movement, thus projecting this particular pin, so that when the movement of lever 15 has been completed and the weight becomes effective, the drum is free to ad-

vance until this particular pin comes into its drum-holding position, thus locating the starting indication, opposite the exposure opening. To illustrate: Assuming pin *x* 5 in Fig. 3 to represent this particular pin, the return movement of the drum will be sufficient to carry it to the position *y* before the lever completes its re-setting movement—the parts being so arranged that this 10 movement must be completed, but not exceeded—whereupon the advancing movement will carry it to the *x* position.

As will be understood, the particular construction shown is simple and efficient in operation, durable in construction, and can be manufactured at a comparatively low cost. And while the structure provides accuracy 15 and ease in operation, the parts are of a character as to withstand rough usage without damage to the parts or to the general 20 operation.

While I have shown the indicating mechanism as particularly adapted for use with game apparatus of a particular type, it 25 will be readily understood that the same is not limited in application to such general or specific use, but may be employed in other relations.

While I have shown and described a preferred embodiment of the invention, it will 30 be readily understood that changes and modifications therein may be found desirable or essential in meeting the exigencies of the particular use to which it may be applied, and I desire to be understood as reserving the right to make any and all such changes or modifications as may be found necessary or desirable, in so far as the same 35 may fall within the spirit and scope of the invention as expressed in the accompanying 40 claims, when broadly construed.

Having thus described my invention, what I claim as new is:

1. In game apparatus wherein a succession of balls or missiles may be projected 45 toward a target having goal values, means for visually indicating the values of goals made, said means including an element rotatable in opposite directions and forming a carrier for indications arranged in a definite value-progression, said element being positioned 50 in definite relationship to an indication exposure opening and having its movements in one direction by a succession of stages 55 and in the opposite direction continuously through an angular distance not less than the angular distances traversed in the totality of stages, and means including control mechanism operative in the element 60 movements in both directions for providing and controlling such element movements, said latter means including power means 65 permanently active to provide element movements in the direction of stage advance, and restraining means normally active to prevent

such element movement and rendered temporarily inactive in the presence of goal value production.

2. In game apparatus wherein a succession of balls or missiles may be projected toward a target having goal values, means for visually indicating the values of goals made, said means including an element rotatable in opposite directions and forming a carrier for indications arranged in a definite value-progression, said element being positioned in definite relationship to an indication exposure opening and having its movements in one direction by a succession of stages to 70 rotate the element through a totality of angular distances of a magnitude determined by the accumulative values of the 75 succession of goals made and in the opposite direction continuously an angular distance not less than such total distance, and means 80 including control mechanism operative in the element movements in both directions for providing and controlling such element movements, said latter means including power means 85 permanently active to provide element movements in the direction of stage advance, and restraining means normally active to prevent such element movement and rendered temporarily inactive in the presence of goal value production.

3. In game apparatus wherein a succession of balls or missiles may be projected toward a target having goal values, means for visually indicating the values of goals made, said means including an element rotatable 90 in opposite directions and forming a carrier for indications arranged in a definite value-progression, said element being positioned in definite relationship to an indication exposure opening and having its movements in one direction by a succession of stages to 95 rotate the element from a predetermined starting position through a totality of angular distances of a magnitude determined by the accumulated values of the succession of 100 goals made and in the opposite direction continuously an angular distance not less than such total distance, and means including control mechanism operative in the element movements in both directions for providing and controlling such element movements, said latter means including power means 105 permanently active to provide element movements in the direction of stage advance, and restraining means normally active to prevent such element movement and rendered temporarily inactive in the presence of 110 goal value production.

4. In game apparatus wherein a succession of balls or missiles may be projected toward a target having goal values, means for visually indicating the values of goals made, said means including an element rotatable 115 in opposite directions and forming a carrier for indications arranged in a definite value- 120 production.

progression, said element being positioned in definite relationship to an indication exposure opening and having its movements in one direction by a succession of stages, to 5 rotate the element from a predetermined starting position through a totality of angular distances of a magnitude determined by the accumulated values of the succession of goals made and in the opposite direction 10 continuously an angular distance not less than such total distance, means for providing the advancing stage movements, and means for providing the movements in the opposite direction, said latter means being operative 15 to return the element an angular distance greater than the total distance of advance from said starting position, said advancing means being operative to locate the element in such starting position, said advancing 20 means including power means permanently active to provide the element advance movements, and restraining means normally active to prevent such power means activity and rendered temporarily inactive in the 25 presence of goal value production.

5. In indicating apparatus of the accumulative type adapted for use with game apparatus having an indication exposure point, an indication-carrying element rotative in 30 opposite directions relative to a predetermined starting position, means for advancing the element in one direction by a succession of stages and including mechanism for selectively determining the angular magnitude 35 of movement of the several stages, and means for moving the element in the opposite direction to locate it relative to such starting position, said latter means being operative to render the selective mechanism 40 temporarily inactive to provide for continuous movement of the element in such opposite directions, an angular distance not less than the totality of distances traversed during the stage advance, said advancing means 45 including power means permanently active to provide the element advance movements, and restraining means normally active to prevent such power means activity and rendered temporarily inactive in the presence 50 of goal value production.

6. In indicating apparatus of the accumulative type adapted for use with game apparatus having an indication exposure point, an indication-carrying element rotative in 55 opposite directions relative to a predetermined starting position, means for advancing the element in one direction by a succession of stages and including power means permanently active to provide element move- 60 ments in such direction, and mechanism normally active to prevent such power means activity and being rendered temporarily inactive in presence of goal value production, said mechanism being operative to selectively 65 determine the angular magnitude of move-

ment of the several stages, and means for moving the element in the opposite direction to locate it relatively to such starting position, said latter movement being continuous and of an angular distance greater than the 70 totality of distances traversed during the stage advance, said mechanism permitting return movement of the element independent of stage control upon completion of the continuous movement and for an angular 75 distance corresponding to the excess movement of the latter means.

7. In indicating apparatus of the accumulative type adapted for use with game apparatus having an indication exposure point, 80 an indication-carrying element rotative in opposite directions relative to a predetermined starting position, means for advancing the element in one direction by a succession of stages and including power means 85 permanently active to provide element movements in such direction, and mechanism normally active to prevent such power means activity and being rendered temporarily inactive in presence of goal value production, 90 said mechanism being operative to selectively determine the angular magnitude of movement of the several stages, and means for moving the element in the opposite direction to locate it relative to such starting position, 95 said latter movement being continuous and of an angular distance greater than the totality of distances traversed during the stage advance, said advancing means being operative to move the element independent 100 of mechanism control in the direction of advance upon completion of the continuous movement and for an angular distance corresponding to the excess magnitude.

8. In indicating apparatus of the accumulative type adapted for use with game apparatus having an indication exposure point, an indication-carrying element rotative in opposite directions relative to a predetermined starting position, means for advancing the element in one direction by a succession of stages, and including mechanism for selectively determining the angular magnitude of movement of the several stages, and means active to render the selective mechanism 110 temporarily inactive and for moving the element in the opposite direction to locate it relative to such starting position, said mechanism including a member operative as a stop, a plurality of members carried by the 115 element and shiftable into and out of the plane of said stop, and control means for shifting said members to provide an escape action of definite length.

9. In indicating apparatus of the accumulative type adapted for use with game apparatus having an indication exposure point, an indication-carrying element rotative in opposite directions relative to a predetermined starting position, means for advanc- 125

- ing the element in one direction by a succession of stages, and including mechanism for selectively determining the angular magnitude of movement of the several stages, and
5 means active to render the selective mechanism temporarily inactive and for moving the element in the opposite direction to locate it relative to such starting position, said mechanism including an escape means oper-
10 able to permit element advance of variable angular distances to provide accumulative advance development by stages, and means for controlling the escape means to limit advancing movements of a stage to definite limits variable as to successive stages.
10. In indicating apparatus of the accumulative type adapted for use with game apparatus having an indication exposure point, an indication-carrying element rotative in opposite directions relative to a pre-determined starting position, means for advancing the element in one direction by a succession of stages, and including mechanism for selectively determining the angular magnitude of movement of the several stages, and means active to render the selective mechanism temporarily inactive and for moving the element in the opposite direction to locate it relative to such starting position, said latter movement being continuous and of an angular distance not less than the totality of distances traversed during the stage advance, said mechanism including an escape means operable to permit element
30 advance of variable angular distances to provide accumulative advance development by stages, and means for controlling the escape means to limit advancing movements of a stage to definite limits variable as to successive stages.
11. In indicating apparatus of the accumulative type adapted for use with game apparatus having an indication exposure point, an indication-carrying element rotative in opposite directions relative to a pre-determined starting position, means for advancing the element in one direction by a succession of stages, and including mechanism for selectively determining the angular magnitude of movement of the several stages, and means active to render the selective mechanism temporarily inactive and for moving the element in the opposite direction to locate it relative to such starting position,
50 said latter movement being continuous and of an angular distance not less than the totality of distances traversed during the stage advance, said mechanism including a stop, a plurality of members shiftable into and out of a position to engage the stop to provide escape action, means for shifting the members into stop-engaging position during advance of the element, control means operative on one or more of the members to shift them out of such position to permit escape by the stop and provide stage advance, and independent means rendered active during element return movement for shifting positioned members to inactive position relative to the stop.
60 and out of the plane of said stop, means operative to shift the members into position to complete stop contact, and control means for shifting one or more positioned members out of such contact to permit stage advance.
65 12. In indicating apparatus of the accu-

mulative type adapted for use with game apparatus having an indication exposure point, an indication-carrying element rotative in opposite directions relative to a pre-determined starting position, means for advancing the element in one direction by a succession of stages, and including mechanism for selectively determining the angular magnitude of movement of the several stages, and means for moving the element in the opposite direction to locate it relative to such starting position, said latter movement being continuous and of an angular distance not less than the totality of distances traversed during the stage advance, 70 said mechanism including a stop, a plurality of members shiftable into and out of a position to engage the stop to provide escape action, means for shifting the members into stop-engaging position during advance of the element, control means operative on one or more of the members to shift them out of such position to permit escape by the stop and provide stage advance, and independent means rendered active during element return movement for shifting positioned members to inactive position relative to the stop.
13. In indicating apparatus of the accumulative type adapted for use with game apparatus having an indication exposure point, an indication-carrying element rotative in opposite directions relative to a pre-determined starting position, means for advancing the element in one direction by a succession of stages, and including mechanism for selectively determining the angular magnitude of movement of the several stages, and means for moving the element in the opposite direction to locate it relative to such starting position, said latter move-
90 ment being continuous and of an angular distance not less than the totality of distances traversed during the stage advance, said mechanism including a stop, a plurality of members shiftable into and out of a position to engage the stop to provide escape action, means for shifting the members into stop-engaging position during advance of the element, control means operative on one or more of the members to shift them out of such position to permit escape by the stop and provide stage advance, and independent means rendered active during element return movement for shifting positioned members to inactive position relative to the stop.
100 14. In indicating apparatus of the accumulative type adapted for use with game apparatus having an indication exposure point, an indication-carrying element rotative in opposite directions relative to a pre-determined starting position, means for advancing the element in one direction by a succession of stages, and including mechanism for selectively determining the angular magnitude of movement of the several stages, and means for moving the element in the opposite direction to locate it relative to such starting position, said latter move-
110 ment being continuous and of an angular distance not less than the totality of distances traversed during the stage advance, said mechanism including a stop, a plurality of members shiftable into and out of a position to engage the stop to provide escape action, means for shifting the members into stop-engaging position during advance of the element, control means operative on one or more of the members to shift them out of such position to permit escape by the stop and provide stage advance, and independent means rendered active during element return movement for shifting positioned members to inactive position relative to the stop, said continuous-movement means being operative to return the element an excess angular distance sufficient to locate a predetermined member in co-operative relation to said member-shifting means to advance the mem-
115 ber into stop-engaging position, whereby the element advancing means may return the element a distance equal to such excess with the advanced member operative to limit the length of return movement.
125 130

14. In indicating apparatus of the accumulative type adapted for use with game apparatus having an indication exposure point, an indication-carrying element rotatable in opposite directions relative to a predetermined starting position, said element carrying a plurality of members shiftable in directions parallel to the element axis, means for shifting the members individually to 5 provide predetermined projection of the members relative to the element, a stationary stop located in the path of a projected member, control means for shifting one or more of the members out of projected position to 10 permit element advancing movement, means for advancing the element an angular distance permitted by the control means operation to produce an advancing movement by stages, and means for moving the element in the opposite direction by continuous 20 movement and for an angular distance not less than the totality of distances traversed during the advancing movement, said means including mechanism for shifting the members in directions to render the control 25 means temporarily inactive.

In testimony whereof, I have signed my name to this specification this 17th day of February, 1919.

WILMUTH E. BLACKBURN.
